UNITED STATES PATENT OFFICE.

EDMUND OCUMPAUGH, JR., OF ROCHESTER, NEW YORK.

CALCULATING-MACHINE.

SPECIFICATION forming part of Letters Patent No. 780,907, dated January 24, 1905.

Application filed May 10, 1904. Serial No. 207,232.

To all whom it may concern:

Be it known that I, EDMUND OCUMPAUGH, Jr., a citizen of the United States, residing at Rochester, in the county of Monroe and State 5 of New York, have invented certain new and useful Improvements in Calculating-Machines; and I do hereby declare the following to be a full, clear, and exact description of the invention, such as will enable others skilled 10 in the art to which it appertains to make and use the same.

This invention relates to calculating-machines, more particularly for calculating wages or interest; and the objects of the invention 15 are to improve the compactness of construction of such mechanism with simplicity of parts and cheapness of manufacture, thereby obviating many of the objections which have heretofore been found in mechanisms of this 20 class.

Further objects of the invention are to provide a mechanism which will afford provision for utilizing both faces of the case for the purpose of calculations, whereby a greater range 25 of calculations may be obtained, and thus greatly enhance the value of the instrument.

To the accomplishment of these objects and such others as may hereinafter appear the invention consists of a calculating-machine embodying the novel features of construction, combination of elements, and arrangement of 30 parts having the general mode of operation, substantially as hereinafter described, and particularly pointed out in the claims.

While the essential and characteristic features of the invention are susceptible of modification, still the preferred embodiment thereof is illustrated in the accompanying drawings, wherein corresponding and like parts 35 are indicated in all the views by the same reference characters, and in which—

Figure 1 shows a plan view of the front face of the assembled mechanism with the case-covers partly broken away, so as to disclose 45 the rollers or drums and the webs or sheets wound thereon. Fig. 2 shows a plan view of the rear face of the assembled mechanism similarly broken away, as in Fig. 1. Fig. 3 shows a sectional view through the upper end of the 50 casing, Fig. 1, disclosing a means for driving

the rollers. Fig. 4 shows a portion of one of the webs or sheets to be wound about the rollers having figures on both sides thereof. Fig. 5 shows a modification, enlarged, which provides means for guiding the bands in close 55 proximity to the slots through which the figures thereon are read. Fig. 6 shows another modification, using two rollers instead of three. Fig. 7 shows the central portion of the webbing when used in one piece on three rollers. 60 Fig. 8 shows an elevational view of a modified form of operating-gear, and Fig. 9 shows a plan view of Fig. 8 with a portion of the casing broken away.

Referring to the drawings, 1 represents a suitable 65 casing in which are conveniently mounted on axles or studs *w y z*, journaled in the casing, a plurality of rollers or drums—in the preferred construction three, designated by A, B, and C—and on which are wound the webbing 70 containing tables of figures from which the calculations are made, as hereinafter fully described. One form of making the webbing for a three-drum calculator is in two portions, as indicated by *e* and *f*, Fig. 5, each being 75 provided with columns of figures forming the tables above mentioned, the web *e* having such columns of figures on both sides thereof and the web *f* on only one side, one of said three series of figures being used on each 80 of said rollers or drums; but, if desired, the tables used in the calculations may be made on a single sheet of webbing *e'*, one portion of its length having markings on both sides and the other portion having markings on one 85 side only, as shown more particularly by Fig. 7. In the construction using two webs or sheets of figures the manner of winding and fastening the same on the drums or rollers is as follows, (referring to Fig. 5:) One 90 web, *e*, has one end clamped in a slot *a'*, extending longitudinally of the drum A, by any suitable or convenient means, as a rod *a''*, wedged closely therein and upon said web, and is then wound clockwise on said drum 95 A and downwardly between drums A and B and is preferably clamped in a slot *b'* in drum B by a rod *b''* in a similar manner, as already described for the end, as drum A. Similarly, 100

one end of the other web, *f*, is secured by a rod *c* in a slot *c* of the drum *C* and after being wound clockwise on said drum is led across the bottom thereof and its other end 5 secured to drum *B* in a similar manner, and preferably at the same point with the end of web *e*. Such a winding will bring the markings on the web *f* about the drum *C* and the marking on the two sides of the web *e* about 10 the two rollers *A* and *B*, to be read on opposite sides thereof.

When but a single piece of webbing *e* is used, a similar winding to that above described is made, and when the webbing has been 15 drawn taut across drum *B* a portion at substantially the center of its length is forced into the slot *b* by the rod *b*. (See Fig. 7.)

The preferable means for operating consists of providing each of the drums *A*, *B*, *C* 20 with gearing, as shown at *a b c*, respectively, mounted on one end of each of the axles or studs *x y z*, and the drums are so spaced apart as to provide for the proper intermeshing of said gears, whereby a movement of one will at 25 the same time drive the others. A convenient means of applying power is afforded by the manipulation of a suitable knob or handle, which may be mounted on one of the axles or studs, as *y*, either upon the outside, Figs. 1 and 2, or 30 inside, Figs. 8 and 9, of the casing *l*, as may be desired. In Figs. 1 and 2 the axle *y* is shown as extending outside the casing, with a knurled wheel *g* acting as an operating-handle mounted on the end thereof. In Figs. 8 and 9 the 35 axle *y* does not extend beyond the casing; but a slot or recess *l* is cut therein, and a knurled wheel *g* of sufficient diameter to project beyond the casing-faces is fitted therein, thus leaving a smooth outer surface to the casing 40 and at the same time forming a handy and efficient operating-handle. It will be readily seen that by turning the operating-handle all of the rollers and the webs carried thereby are turned so as to bring successive portions 45 thereof in view on the outside portions of said rollers. To take up any lost motion and to prevent the webbing from leaving the position in which it is desired to place it by reason of its own inherent spring from being tightly 50 wound, the preferable means employed is a spring *h* of any suitable and convenient form, which is suitably secured by one end to the casing *l*, as at *i*, and placed in position to bear outwardly upon the handle, and thus prevent 55 it from turning beyond the desired point.

On each side of each face of the casing *l* are placed grooves or guideways *k*, in which are adapted to be placed scale or index cards *m* and *n*, secured in said grooves and protected 60 from wear by a slide of any suitable transparent material, as celluloid, mica, glass, or the like, as indicated by *o*. The index-cards *m* and *n* when used to calculate wages are each provided with longitudinally-extending rows 65 of figures, as follows: On each side of a slot

n', preferably arranged centrally in the card *n* in order to coincide with drum *B*, are arranged columns of figures indicating an amount of pay per week covering the range as ordinarily used by business concerns and 70 the amount per day, hour, and half-hour at the rate of nine hours per day, or fifty-four hours per week. Similarly index-card *m* is arranged with columns of figures indicating an amount of pay per week similar to that on card *n*, having, preferably, between them a column indicating the amount per day, and preferably 75 outside thereof in order to coincide with drums *A* and *C* are slots *m'* and *m''* and further columns indicating the amount due per hour and 80 half-hour at the rate of eight and ten hours per day, or forty-eight and sixty hours per week. The slots on these index-cards, as above indicated, are so located as to register 85 with the longitudinal axes of the drums *A*, *B*, and *C*, so that the markings on the webbing passing over the drums may be easily read through the slots. It is of course understood 90 that the use of eight, nine, and ten hours per day labor is merely arbitrary, and the index-cards may be marked and arranged for any number of hours as may be selected as convenient or necessary.

As above noted, the webs or sheets may be used for various calculations; but I will here 95 describe their markings when used for calculating wages in combination with the index-cards as above set forth. For such calculation the webbing is preferably provided with a series of columns of figures from "1" to 100 "48" and "1" to "54" on the two sides of web *e* and from "1" to "60" on one side of web *f* when made in two portions and when made of a single sheet with columns of figures from "1" to "60" and from "1" to "54" on 105 opposite end of one side and from "1" to "48" on one end of the reverse side. (See Fig. 7.) Each of these columns is preferably headed by a numeral in heavy type or printed in different-colored ink from the remainder of 110 the figures. Below each of these heavy figures, which indicate the number of hours per week the workman has actually put in, are placed columns of figures indicating the amount to be received for such hours of labor 115 at the rate per week as indicated by the index-card at which they are found opposite as the drum is turned.

The operation of the device may now be described as follows: To figure up the amount due a workman in any given week; it is only necessary to know how many hours he has worked, his rate per week or per hour, and the number of hours per day which make for him a full day's work. Say his regular time 120 is eight hours per day at twenty-four dollars per week, or fifty cents per hour, and he has worked in all forty hours during the week. Then by turning the operating-handle so that 125 the heavy type-numeral "40" appears at the 130

head of the slot m' opposite "\$24.00" in the column indicating the pay per week, or "50 cents," indicating the pay per hour, will be found "\$20.00," the amount due him on such basis for his forty hours' work, (see Fig. 1,) and so for any amount for a given time within the range of the figures printed on the webs and the scale or index cards.

It should of course be understood that the arrangement of scale or index cards and transparent holders therefor is only one of many arrangements that may be used—as, for instance, the columns of figures on the index-cards may be placed directly on the transparent material, the same being darkened by any well-known means, as by tinting with pigment, except for a portion corresponding to the slots hereinbefore mentioned, as may be seen by reference to Figs. 1 and 2.

It may be found convenient to bring the webs nearer to the slots through which the calculated amounts of pay are read and to stretch the web taut, and to this end I may arrange small slats or guides, as shown at p , Fig. 5, just below the slots, and provided with curved surfaces, so that the webs may readily slide over them; but, as a rule, these slats or guides are not found necessary, the webs lying tightly on the rollers or drums, as shown by Fig. 3, and are easily read while in such position.

The modification shown in Fig. 6 discloses the use of two rollers or drums A' and B' instead of three, connected by a single piece of webbing f'' , having its ends wound clockwise on said drums and having markings for calculations on both sides. By this arrangement the range of calculation is cut down by one-third; but the efficiency within the range remaining is not altered, and the principle and construction being the same as that already described it is not deemed necessary to more fully explain the same.

While the invention has been described with particular reference to the details of construction, it should be understood that the same is not limited thereto, as many and various changes, alterations, and substitutions may be made therein and still fall within its scope and principle; but

What I do claim, and desire to secure by Letters Patent, is—

1. In a calculating-machine the combination with at least three web-holding rollers, of a suitable casing therefor provided with slots adapted to register with said rollers, means for operating said rollers, and webbing marked on both sides on one portion and on one side only on another portion mounted on said rollers in such manner that calculations may be made from each marked portion through said slots, substantially as described.

2. In a calculating-machine the combination with at least three web-holding rollers, of a suitable casing therefor provided with slots

adapted to register with said rollers, gearing connecting said rollers, means for operating said gearing, and webbing marked on both sides on one portion and on one side only on another portion mounted on said rollers in such manner that calculations may be made from each marked portion through said slots, substantially as described. 70

3. In a calculating-machine, the combination with a suitable casing open on two sides, of at least three web-holding rollers journaled therein, means for operating said rollers, and webbing marked on both sides on one portion and on one side only on another portion mounted on said rollers, in such manner that calculations may be made from each marked portion and from both open sides of said casing, substantially as described. 75

4. In a calculating-machine the combination with a suitable casing open on two sides, of at least three web-holding rollers journaled therein, gearing connecting said rollers, a handle for operating said gearing, and webbing marked on both sides on one portion and one side only on another portion, mounted on said rollers in such manner that calculations may be made from each marked portion and from both open sides of said casing, substantially as described. 80

5. In a calculating-machine the combination with a suitable casing open on two sides, of at least three web-holding rollers journaled therein, means for operating said rollers, webbing marked on both sides on one portion and on one side only on another portion mounted on said rollers in such manner that calculations may be made from each marked portion and from both open sides of said casing, substantially as described. 90

6. In a calculating-machine the combination with a suitable casing open on two sides, of at least three web-holding rollers journaled therein, means for operating said rollers, slotted slides mounted over said open sides suitably scaled and indexed, and webbing marked on both sides on one portion and on one side only on another portion, mounted on said rollers in such manner that calculations may be made from each marked portion and from both open sides of said casing through the slots in said slides, substantially as described. 105

7. In a calculating-machine, the combination with three web-holding rollers, of a suitable casing therefor provided with slots adapted to register with said rollers, means for operating said rollers, webbing having the outer portions secured to the outer rollers and the central portion to the inner roller, and marking on said webbing so that calculations may be made through each of said slots, substantially as described. 120

8. In a calculating-machine the combination with three web-holding rollers, of a suitable casing therefor provided with slots adapted to 130

register with said rollers, means for operating said rollers, webbing having the outer portions wound on the outer rollers and the central portion secured to the inner roller, and 5 having markings on both sides on one portion and on one side only on another portion whereby calculations may be made from each marked portion through said slots, substantially as described.

10 9. In a calculating-machine the combination with a suitable casing open on two sides, of three web-holding rollers journaled therein, means for operating said rollers, webbing having the outer portions secured to the outer 15 rollers and the central portion to the inner roller, and marking on said webbing so that calculations may be made from both open sides of said casing, substantially as described.

10 10. In a calculating-machine the combination with a suitable casing open on two sides, of three web-holding rollers journaled therein, means for operating said rollers, and webbing having the outer portions wound clockwise on the outer rollers and the central portion 25 secured to the inner roller and having markings on one side only on one portion and on both sides on another portion, whereby calculations may be made from both open sides of said casing, substantially as described.

30 11. In a calculating-machine the combination with a suitable casing open on two sides, of three web-holding rollers journaled therein, means for operating said rollers, a web wound clockwise on one outer roller, a second web 35 wound clockwise on the other outer roller, the free ends of said webs both secured to the inner roller, and markings on said webs so that calculations may be made from both open sides of said casing, substantially as described.

40 12. In a calculating-machine the combination with a suitable casing open on two sides, of three web-holding rollers journaled therein, means for operating said rollers, a web wound clockwise on one outer roller, a second web 45 wound clockwise on the other outer roller, the free ends of said webs both secured to the inner roller at the same point, and markings on said webs so that calculations may be made from both open sides of said casing, substantially as described.

50 13. In a calculating-machine the combination with a suitable casing open on two sides, of three web-holding rollers journaled therein, gearing connecting said rollers, an operating-handle mounted on one of said rollers, a web wound clockwise on one outer roller, a second web wound clockwise on the other outer roller, the free ends of said webs both secured to the inner roller, and markings on 60 said webs so that calculations may be made from both open sides of said casing, substantially as described.

55 14. In a calculating-machine the combination with a suitable casing open on two sides, of three web-holding rollers journaled therein, 65

gearing connecting said rollers, means for operating and means for taking up lost motion in said gearing, a web wound clockwise on one outer roller, a second web wound clockwise on the other outer roller, the free ends of 70 said webs both secured to the inner roller, and markings on said webs so that calculations may be made from both open sides of said casing, substantially as described.

15. In a calculating-machine the combination with a suitable casing open on two sides, of three web-holding rollers journaled therein, means for operating said rollers, a web wound clockwise on one outer roller, a second web wound clockwise on the other outer roller, the free ends of said webs both secured to the inner roller, markings in said webs so that calculations may be made from both open sides of said casing, and guides for holding the webs in proximity to said open sides, substantially as described.

16. In a calculating-machine the combination with a suitable casing open on two sides, of three web-holding rollers journaled therein, gearing connecting said rollers, means for 90 operating and means for taking up lost motion in said gearing, a web wound clockwise on one outer roller, a second web wound clockwise on the other outer roller, the free ends of said webs both secured to the inner roller, 95 markings on said webs so that calculations may be made from both open sides of the casing, and guides for holding the webs in proximity to said open sides, substantially as described.

100 17. In a calculating-machine the combination with a suitable casing open on two sides, of three web-holding rollers journaled therein, means for operating said rollers, slotted slides mounted over said open sides suitably sealed or indexed, a web wound clockwise on one outer roller, a second web wound clockwise on the other outer roller, the free ends of said webs both secured to the inner roller, and markings on said webs so that calculations may be made from both open sides of 110 said casing through the slots in said slides, substantially as described.

115 18. In a calculating-machine the combination with a suitable casing open on two sides, of three web-holding rollers journaled therein, gearing connecting said rollers, means for operating said gearing, slotted slides mounted over said open sides suitably sealed or indexed, a web wound clockwise on one outer roller, a second web wound clockwise on the other outer roller, the free ends of said webs both secured to the inner roller, and markings on 120 said webs so that calculations may be made from both open sides of said casing through the slots in said slides, substantially as described.

125 19. In a calculating-machine the combination with a suitable casing open on two sides, of three web-holding rollers journaled there- 130

in, gearing connecting said rollers, means for operating said gearing, slotted slides mounted over said open sides suitably scaled or indexed, a web wound clockwise on one outer roller, a 5 second web wound clockwise on the other outer roller, the free ends of said webs both secured to the inner roller, markings on said webs so that calculations may be made from both open sides of said casing through the

slots in said slides, and guides for holding the 10 webs in proximity to said slots, substantially as described.

In testimony whereof I affix my signature in presence of two witnesses.

EDMUND OCUMPAUGH, JR.
